UNITED STATES PATENT OFFICE.

THOMAS G. OTTERSON, OF WOODBURY, NEW JERSEY.

PRESERVE-JAR FASTENING.

SPECIFICATION forming part of Letters Patent No. 377,687, dated February 7, 1888.

Application filed September 14, 1886. Serial No. 213,506. (No model.)

To all whom it may concern:

Be it known that I, THOMAS G. OTTERSON, a citizen of the United States, residing at Woodbury, in the county of Gloucester and State of New Jersey, have invented certain new and useful Improvements in Preserve-Jar Fastenings, of which the following is a specification, reference being had therein to the accompanying drawings.

10 Figure 1 represents a side elevation of a preserve-jar fastening embodying my invention. Fig. 2 represents a vertical section thereof in line $x-x$, Fig. 1. Fig. 3 represents a top or plan view thereof. Fig. 4 is a perspective view of a modification of the yoke and valve. Fig. 5 is an enlarged detail of the valve.

Similar letters of reference indicate corresponding parts in the several figures.

20 My invention consists of a preserve-jar fastening formed of a clamp or yoke which is adapted to engage with spiral lugs or threads on the neck of the jar, and connected centrally to a button or valve, made of rubber or other 25 soft material, which is compressed against the lid of the jar and tightly closes a vent therein. Provision is made for permitting the clamp or yoke and button or valve to roll on each other, all as will be hereinafter fully described.

30 Referring to the drawings, A represents a fruit or preserve jar, and B the lid thereof, the latter having a vent, C, for admission of air into the jar when the same is to be opened.

D represents a clamp or yoke formed of a 35 strip of steel or other suitable metal or material, or of wire, and having its ends bent downwardly, the terminations thereof being turned inwardly, forming lips E, which are adapted to engage with spiral lugs or threads 40 F on the body of the jar; or the clamp or yoke may be made of wire, as shown in Fig. 4, its ends being suitably bent to engage under the lugs F. On the under side of the clamp or yoke, at the center thereof, is a button or valve, G, made of rubber or any other suitable material or substance. This is attached securely 45 to the lower end of the pin H, the shank of which passes up through a hole in the clamp or yoke, while its upper end is beaded. Thus 50 the clamp or yoke will freely rotate on the pin and over the button or valve. This button or valve is in the form of a disk. On the upper

side of this button or valve the construction is such that should there be any irregularity in the lid, gasket, or shoulder of the jar, or the 55 clamp or yoke, button or valve, pin or packing of the fastening, the clamp or yoke and button or valve may, when the lid is being secured upon the jar, roll on each other, avoiding breakage or injury to the parts, especially 60 chipping of the center of the lid when made of glass; or, if desired, there may be placed a spiral spring, K, about the shank of the pin H, and between the button or valve and the clamp or yoke, which will give the same results in an equivalent way.

The top of the lid has a recess, L, to receive the button or valve G, and the wall around the vent C is slightly raised, so that the button or valve rests thereon, thus avoiding direct 70 contact of the body of the button or valve with the lid and consequent injury to the latter when pressure is applied to the button or valve by the action of the clamp or yoke. A gasket, M, between the shoulder α on the upper 75 part of the jar and the under side of the ends of the lid, is employed, and when the lid and the clamp or yoke with its connected button or valve are applied in position the clamp or yoke is rotated, and as it engages with the 80 spiral lugs or threads of the jar and is drawn downwardly it forces the lid firmly on its seat, tightly closing the jar and surely retaining the lid in position. The button or valve is also forced by the clamp or yoke against the 85 lid and compressed on the same around the wall of the vent, so that the vent is reliably closed. The button or valve does not rotate with the clamp, but remains fixed on the lid, thus avoiding any liability to injure the lid, 90 especially around the wall of the vent. The upper side of the valve being plane, it is adapted to rest against the yoke or clamp and permit it to rotate easily thereon while the lid is being fastened to the jar.

In order to open the jar, the clamp or yoke is properly rotated or unscrewed, the button or valve being raised therewith, thereby uncovering the vent C and permitting air to enter the jar.

Having thus described my invention, what I claim as new, and desire to secure by Letters Patent, is—

1. A jar having spiral lugs and a lid hav-

ing a vent and a recess in its upper face, in combination with a button or valve, pin, and clamp or yoke, said button or valve resting in said recess, and being pivoted to the clamp or yoke by the said pin, substantially as described.

2. The jar A, having spiral lugs, in combination with the lid B, having vent C and recess L, button or valve G, clamp or yoke D, having lips E, and pin H, pivoted to said clamp, substantially as and for the purpose set forth.

3. The jar A, having spiral lugs, in combination with the lid B, having vent C and recess L, clamp or yoke D, having lips E, button or valve G, resting in recess L, and gasket M and pin H, pivoted to said clamp, substantially as described.

4. In a preserve-jar fastening, the combination of the following elements, viz: a lid centrally perforated, a clamp or yoke having bent ends for engaging under the spiral lugs of the jar, a valve pivoted centrally in and to the clamp or yoke by means of a headed pin, the upper side of the valve being plane and arranged to rest against the clamp or yoke and permit it to rotate easily thereon while the lid is being fastened on the jar, substantially as described.

In testimony whereof I affix my signature in presence of two witnesses.

THOMAS G. OTTERSON.
